[57] CLAIM

The ornamental design for a rack for elongated objects, as shown and described.

DESCRIPTION

FIG. 1 is a top, left side perspective view of a rack for elongated objects;

FIG. 2 is a right side elevational view of FIG. 1, the left side being a mirror image;

FIG. 3 is a fragmented front elevational view of FIG. 1;

FIG. 4 is a fragmented rear elevational view of FIG. 1;

FIG. 5 is a fragmented top plan view of FIG. 1;

FIG. 6 is a fragmented bottom plan view of FIG. 1;

FIG. 7 is a top, left side perspective view of a second embodiment of FIG. 1;

FIG. 8 is a right side elevational view of FIG. 7, the left side being a mirror image;

FIG. 9 is a fragmented front elevational view of FIG. 7;

FIG. 10 is a fragmented rear elevational view of FIG. 7;

FIG. 11 is a fragmented top plan view of FIG. 7; and,

FIG. 12 is a fragmented bottom plan view of FIG. 7.

The rack is fragmentally shown in FIGS. 3-6 and 9-12 for convenience of illustration.
